UNITED STATES PATENT OFFICE.

JACOB S. AMMON, OF READING, PENNSYLVANIA.

APPARATUS FOR COMBINING ANÆSTHETICS.

SPECIFICATION forming part of Letters Patent No. 395,683, dated January 8, 1889.

Application filed September 12, 1888. Serial No. 285,220. (No model.)

To all whom it may concern:

Be it known that I, JACOB S. AMMON, a citizen of the United States, residing at Reading, in the county of Berks and State of Pennsylvania, have invented certain new and useful Improvements in Apparatus for Combining Anæsthetics; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 The object of this invention is to provide an apparatus in which anæsthetic agents may be conveniently stored and when wanted readily applied to the patient, combined in varying proportions, if desired, and properly aerated 20 without the loss and inconvenience occasioned by allowing the vapor to be distributed to a greater or less extent throughout the room.

Figure 1 is a longitudinal section of the anæsthetic-chamber and its inclosing and supporting case. Fig. 2 is an end view and partial cross-section of the same, the hinged lid of the case being open and the position of the chamber when oscillated being indicated by dotted lines.

30 A represents a square-cornered wooden box or case provided with a hinged cover, A'.

B is a closed semi-cylindrical sheet-metal chamber divided, as here shown, into two compartments by a partition, B². A nozzle, C, 35 with internal screw-thread, C', by means of which the inhaler may be attached, projects from the front wall of the first compartment, its center coinciding with the center of the curved bottom of the chamber. A corresponding trunnion-piece, B⁴, projects from the back wall, and on these the chamber is pivotally supported in the case A, though held firmly when the cover A' is closed.

The nozzle C, which serves also as a front 45 trunnion, extends into the first compartment, and is attached to or forms part of an outlet-tube, C², which is bent downward, so that its mouth will be near the level of the fluid anæsthetic agent placed in the compartment. 50 In this outlet-tube is placed a faucet or other suitable cock, E, which projects through the top of the chamber, and is provided with a

handle, E', or other suitable means of turning it, so as to close or open the outlet to any desired extent.

55 A screw-plug, F, closes an inlet-opening in the top of the compartment, through which the fluid agent and the air required by the patient with the vapor is admitted.

Vertical open partitions G (represented as 60 formed of parallel wires soldered or otherwise secured in position) serve the purpose of retaining an absorbent material, H—such as sponge—close against the sides and top of the compartment, where in the normal position of 65 the chamber the fluid will either not touch it at all or only touch the lower part of it.

The second compartment and any others 70 that may be used are provided with inlet and outlet openings and tubes, regulating-cocks, 75 and an absorbent material in the same manner as the first compartment, above described, the only difference being that the nozzle C³ of the outlet-tubes of the rear compartments will extend through the partition or partitions into the first compartment, as shown in Fig. 1, the mixing or combining of the several vapors with each other being effected entirely in this compartment.

75 When the case is closed and locked, the apparatus may be easily and safely carried around with the liquid anæsthetic agents in the several compartments, the chamber B being held firm. When it is desired to anæsthetize a patient, an inhaler is attached, the 80 cover of the case is opened wide, and the chamber is oscillated, so as to bring the several fluids in contact alternately with the materials H on either side, which latter are thus saturated. When the chamber is brought to 85 rest, the surplus fluid drops to the bottom. Supposing the first compartment to contain ether and the second chloroform, if it is desired to apply the former only, the cock E and plug F of the second compartment are left 90 closed, while those in the first compartment are each opened as far as desired. The air admitted is compelled to enter the outlet-tube C² near the bottom of the compartment and the level of the fluid, and on its passage 100 is brought in contact and mixed with the vapor thrown off from the saturated surface of the absorbent material, as well as from the surface of the fluid, and the ether-vapor thus

aerated is inhaled by the patient. If it is found desirable to combine with the ether a portion of the chloroform, the corresponding plug and cock of the second compartment 5 may be opened a proper distance and the aerated chloroform-vapor be admitted to the first compartment through the nozzle C³. As soon as a sufficient amount of the latter has 10 been used, it may be entirely closed off. If other compartments and agents are used, the method of combining is the same. Owing to the fact that these vapors are heavier than air there will be no appreciable waste, even if both the outlet and inlet openings are left 15 open when not in actual use; but it is preferable to close the nozzle C with a plug or cap, D, at such times.

The advantages of having these important but more or less dangerous agents fully under control, and of avoiding waste and annoyance to the operator, secured by my apparatus, as compared with the ordinary means employed, will be easily understood.

The preferred construction herein described 25 may be readily varied without departing from the spirit of my invention; and I do not therefore limit myself closely to such a construction; but

What I desire to secure by Letters Patent 30 are the following claims:

1. In an apparatus for vaporizing and aerating anæsthetics, the pivoted chamber provided with inlet and outlet openings and an absorbent material, H, adapted to be wet by 35 the oscillation of said chamber, substantially as set forth.

2. In an apparatus for vaporizing and aerating anæsthetics, the pivoted chamber provided with inlet and outlet openings, an outlet-tube extending downward to near the fluid- 40

level, and an absorbent material, H, adapted to be wet by the oscillation of said chamber, substantially as set forth.

3. In an apparatus for combining anæsthetics, an oscillating chamber divided into 45 two or more compartments, each of which is provided with inlet and outlet openings, and outlet-tubes with regulating-cocks converging from near the fluid-level of each compartment toward the mixing-compartment and 50 from said mixing-compartment to an inhaler-nozzle, substantially as set forth.

4. In an apparatus for vaporizing or combining anæsthetics, an oscillating semi-cylindrical chamber, B, provided with inlet and outlet openings, and with an absorbent material, H, normally retained above the fluid-level, substantially as described, in combination with an inclosing and supporting case, A, substantially as set forth. 55

5. In an apparatus for combining anæsthetics, the chamber B, divided into two or more compartments, each of which is provided with inlet and outlet openings, and outlet-tubes converging toward the first or mixing compartment, substantially as set forth. 65

6. In an apparatus for combining anæsthetics, the oscillating chamber B, divided into two or more compartments, each of which is divided into inlet and outlet openings, and outlet-tubes converging toward the first or mixing compartment, each compartment containing an absorbent material, H, arranged substantially as set forth. 70

In testimony whereof I affix my signature in 75 presence of two witnesses.

JACOB S. AMMON.
